ABSTRACT: A cyclone separator has in its outlet for the light fraction a vortex finder, the outwardly facing part of which is divided by a plurality of radially disposed partition walls joined by an elongate nave extending coaxially with the separation chamber of the separator. The nave protrudes outwardly from the outlet to constitute a distance member for a wall of a casing for the separator and also to define in conjunction with the casing wall and the end of the outlet an annular slot for radially deflecting the partial flows of the light fraction passing between the partition walls.

**CLYCLONE SEPARATOR TO BE BUILT IN A CASING OR
SIMILAR**

This invention refers to cyclone separators, such as are intended to be built-in in a casing or similar structures and are provided with a central outlet, in which, on separating, the outgoing light fraction is divided into parallel partial flows by preferably radially arranged partitions. It is customary to construct such outlets so that they rest against the wall of the casing along a part of their circumference in order to define, in axial direction, the position of the cyclone in the casing. However, in that case it has been found that when fiber suspensions are separated certain problems may arise as, due to whirl formations or other causes, the fibers contained in the suspension exhibit a tendency to twist together into long threads, which adversely affect the quality of the final product. According to the invention this disadvantage is avoided by constructing the central outlet as described in detail hereinafter.

The invention will now be described more in detail with reference to the enclosed drawing, which shows, in FIG. 1, a side view of a cyclone separator in a partial longitudinal section and, in FIG. 2, an end view of one of the outlets of the separator.

The cyclone separator 1 is provided with one or more tangential inlets 2, through which the suspension containing the material to be separated is fed into the separation chamber 1a at one end thereof. The chamber tapers conically towards the other end where, in the usual manner, there is a central outlet 1b for the heavy fraction or separation component of the material. At the opposite end of the chamber there is a central outlet 10 for the light fraction. This outlet is constructed as a Venturi-shaped nozzle in a removably arranged end part 3 closing this end of the separator. The nozzle chamber 4 widens conically towards its two ends and is provided, in the outer part 10a, with radially arranged partitions 5, through which the outflowing material is divided into partial flows parallel to each other. The partitions are joined in the central part of the channel by a central nave or hub part 6, which, as best seen in FIG. 2 is rod-shaped and extends a short distance outside the mouth of channel part 10a and abuts at its outer end against a wall of a casing 7 enclosing the separator; said casing may be common for a plurality of separators of the same construction. The distance of the mouth of the channel 4 from the casing wall is such that between the outer end 8 of the nozzle and the wall of the casing 7 a ring-shaped slot 11 is formed by means of which the outgoing light fraction is spread radially outwards and is discharged without danger of the fibers becoming twisted together by whirl formations. At the same time, due to the partitions, the rotation of the flow of material is arrested

on recovery of pressure energy.

The apparatus according to the invention is particularly advantageous for use in multiple cyclone separator plants. Such a plant usually contains a plurality of cyclone separators enclosed in a common casing in which each separator must have a carefully fixed position and it should be easily and quickly removable for overhaul and exchange or for cleaning. As it is evident, especially in this kind of plants twistings of fibers into long threads easily could have a disastrous effect upon the operation of the plant and, hence, it is of crucial importance that twistings of fibers is prevented.

An especially suitable embodiment of multiple cyclone separator plants as above referred to is described in Swedish Pat. No. 200,549.

15 I claim:

1. A cyclone separator for separating material including fibers suspended in a liquid suspension into a light fraction containing the fibers and a heavy fraction containing rejects, said cyclone separator comprising:

20 a generally conical separation chamber having at its narrow end an outlet for the heavy fraction of the material and at its wide end an outlet for the light fraction of the material; and

25 a vortex finder mounted in the outlet for the light fraction, said vortex finder including an elongate closed nave disposed coaxially with said chamber, and a plurality of partition walls joined along an edge to the nave and radially extending from said nave to a wall of the vortex finder surrounding said nave.

30 2. The cyclone separator according to claim 1 wherein said nave protrudes from the outer end of said outlet for the light fraction.

35 3. The cyclone separator according to claim 1 wherein said vortex finder defines a Venturi-shaped nozzle, said nave and said partition walls being disposed in the outwardly facing part of the nozzle.

40 4. The cyclone separator according to claim 1 wherein said partition walls are flat walls, said edge of the partition walls being parallel to the center axis of the nave.

45 5. The cyclone separator according to claim 1 and comprising a casing including a wall portion disposed substantially parallel to the outer end of said outlet for the light fraction spaced apart therefrom, and wherein a portion of said nave protrudes from said outlet end into abutment with said wall portion, the protruding nave portion consisting a distance member defining about said nave portion an annular slot of predetermined width between said casing wall portion and said outlet end, said slot deflecting the light fraction in radial direction.

[57] ABSTRACT

A cyclone separator has in its outlet for the light fraction a vortex finder, the outwardly facing part of which is divided by a plurality of radially disposed partition walls joined by an elongate nave extending coaxially with the separation chamber of the separator. The nave protrudes outwardly from the outlet to constitute a distance member for a wall of a casing for the separator and also to define in conjunction with the casing wall and the end of the outlet an annular slot for radially deflecting the partial flows of the light fraction passing between the partition walls.

**REEXAMINATION CERTIFICATE
ISSUED UNDER 35 U.S.C. 307**

THE PATENT IS HEREBY AMENDED AS
INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS
BEEN DETERMINED THAT:

The patentability of claim 2 is confirmed.

Claims 1, 3 and 4 are cancelled.

Claim 5 is determined to be patentable as amended.

New claim 6 is added and determined to be patentable.

5. The cyclone separator according to claim 1 and comprising a casing including a wall portion disposed substantially parallel to the outer end of said outlet for the light fraction and spaced apart therefrom, and wherein a portion of said nave protrudes from said outlet end into abutment with said wall portion, the protruding nave portion [consisting] constituting a [distance] distancing member [defining] which defines about said nave portion an annular slot of predetermined width between said casing wall portion and said 35

outlet end, said slot deflecting the light fraction in radial direction.

6. *A cyclone separator for separating material including fibers suspended in a liquid suspension into a light fraction containing the fibers and a heavy fraction containing rejects and which employs partitions to prevent the twisting together of fibers in the light fraction and to recover pressure energy, said cyclone separator comprising:*

a generally conical separation chamber having at its narrow end an outlet for the heavy fraction and at its wide end an outlet for the light fraction;

a vortex finder having means for preventing the twisting together of fibers and for recovering pressure energy mounted in the outlet for the light fraction, said means including an elongate nave disposed coaxially with said chamber and a plurality of partition walls for positioning the nave and for dividing the light fraction into adjacent partial flows and for arresting the rotation of said flows, said partition walls being joined along an edge to the nave and extending radially from said nave to a wall of the vortex finder surrounding said nave, said nave protruding from the outer end of said outlet for the light fraction; and

a casing to receive the light fraction, said casing including a wall portion disposed substantially parallel to the outer end of said outlet for the light fraction and spaced apart therefrom, and wherein a portion of said nave protrudes from said outlet and into abutment with said wall portion, the protruding nave portion constituting a distancing member which defines about said nave portion an annular slot of predetermined width between said casing wall portion and said outlet, said slot deflecting the light fraction in radial direction.
